UNITED STATES PATENT OFFICE.

OTTO H. ERICKSON, OF MINNEAPOLIS, MINNESOTA.

ARTIFICIAL LIMB.

Application filed May 16, 1925. Serial No. 30,718.

My invention relates to artificial legs, and has for its object to improve the same in the several particulars hereinafter noted.

To the above end, the invention consists of 5 the novel devices and combinations of devices hereinafter described and defined in the claims.

In the accompanying drawings, which illustrate the invention, like characters indicate like parts throughout the several views.

Referring to the drawings:

Fig. 1 is a side elevation of an artificial leg having the invention embodied therein, with some parts broken away and sectioned;

15 Fig. 2 is an isometric view of the shank extension and knee joints;

Fig. 3 is a fragmentary isometric view of the upper end portion of the shank;

20 Fig. 4 is a bottom plan view of the artificial leg;

Fig. 5 is a detail view with some parts sectioned substantially on the line 5—5, on an enlarged scale;

25 Fig. 6 is a fragmentary detail view principally in central vertical section taken through the front portion of the shank extension and socket, on an enlarged scale; and

Fig. 7 is a fragmentary detail view showing a slight modification of the method of 30 attaching the heel to the foot.

The artificial leg illustrated is for an amputation below the knee, and of the parts thereof, it is important to note the foot 8, shank 9, socket 10, thigh lacer 11, and knee joints 12 connecting said socket to the thigh lacer.

35 The foot 8 and shank 9 are connected by an ankle joint shell 13 having a pair of axially spaced circumferentially extended bearing ribs 14 and which shell and ribs are mounted in seats in said foot and shank. A leather bearing 15 is interposed between the foot 8 and ankle joint shell 13 and extends the full length of said shell. The ankle joint shell 13 is secured to the shank 9 by a pair of nut-equipped studs 16 and to the foot 8, by a screw-threaded T stud 17 having a nut 18 mounted in a recess 19 in the bottom of said foot.

40 To keep the ankle joint properly lubricated, there is mounted in the foot 8, below and slightly forward of the ankle joint 13, a transversely extended cylindrical grease container 20 one end of which is permanently closed. Mounted in the other end of 45 the grease container 20 is a grease pressure

device in the form of a screw plug 21 having screw-threaded engagement therewith. This screw plug 21 has a transverse notch adapted to receive a screw driver by which said screw 60 plug may be turned. Formed in the foot 8 and extending through the leather bearing 15 is a pair of grease ducts 22 leading from the grease container 20 to the ankle joint shell 13 at its bearing ribs 14. Obviously by 65 screwing the screw plug 21 into the container 20, the grease therein will be forced through the ducts 22 to the ankle joint.

Interposed between the foot 8 and the shank 9 forward of the ankle joint is a 70 cushion stop 23 and interposed between said foot and shank rearward of said ankle joint is a heel spring 24 encased in a leather shell 25.

75 The sole 26 of the foot 8 is held in position partly by a pair of screws 27 located near the rear end portion thereof, and said sole rearward of the screws 27 is loose. The foot 8 is provided with a resilient, pliable heel 28, the forward portion of which is 80 wedge-shaped and loosely inserted under the rear end portion of the sole 26, and its rear end portion is held by a T-strap 29 secured to the foot 8. This heel 28 covers the nut 18 and the recess 19, and access may be had to 85 said nut by buckling the heel 28 to withdraw its wedge-shape front end portion from under the sole 26 and then moving said heel forward out of the strap 29.

90 Referring now to the modification shown in Fig. 7, the heel 30 is identical with the heel 28 with the exception that the same is provided with one or more dowel pins 31 inserted into seats 32 in the foot 8 and cemented or otherwise secured thereto. By 95 buckling the heel 30, the wedge-shaped forward end portion thereof may be withdrawn from under the sole 26 and then the heel bent backwards without removing the dowel pins 31 from their seats 32 to afford access to the 100 nut 18.

One of the primary objects of my present invention is to produce a shank or other leg member and a socket therefor that have more nearly the appearance and size of the natural leg and at the same time have the required strength, weight and bearing surfaces between the leg member and socket.

105 To produce a relatively thin leg member and socket, as shown, I provide the shank 9 with a thin metallic upper extension 33 and form on the exterior of the socket 10, upper

and lower bearing shoulders 34 and 35, respectively, which rest on the upper edges of the shank extension 33 and shank 9, respectively, and support said socket from the shank. The shoulder 34 has continuous circumferential engagement with the upper edge of the socket extension 33, and the shoulder 35 has continuous circumferential engagement with the upper edge of the shank 9. The upper shoulder 34 and upper edge portion of the shank extension 33 have a greater diameter than the shoulder 35 and upper edge portion of the shank 9 so that the socket 10 telescopes into the shank 9 and its extension 33.

To securely attach the shank extension 33 to the shank 9, said extension has formed in its lower edge portion, a plurality of notches 36 which are circumferentially spaced to leave a plurality of circumferentially spaced wide prongs 37 therebetween. The lower edge portion of the shank extension 33 and its prongs 37 are telescoped onto the shank 9 and the outer face of said shank is externally reduced at 38 to receive said extension and prongs to countersink the same into the shank 9 so that the outer faces of said extension and prongs are flush with the exterior of said shank. In addition to the interlocking engagement of the prongs 37 with the shank 9, the shank extension 33 is further secured to the shank 9 by a plurality of rivets 39 inserted through each prong 37 and the shank 9.

Applied around the shank 9 is a shell 40, preferably of raw hide, and which shell extends upward onto the shank extension 33 to a point above its prongs 37 and covers the joint between the shank 9 and its extension 33 and reinforces the same.

Applied around the upper end portion of the shell 40 is a band of leather 41 or other suitable material which extends onto the shank extension 33 slightly above the upper edge of the shank 39 and cover the same, and further reinforces the joint between the shank 9 and its extension 33.

What I claim is:

1. An artificial leg member, a thin metallic upper extension telescoped onto said leg member and rigidly secured thereto, an outer covering shell applied around said leg mem-

ber and extended up to said upper extension, a band applied around the upper portion of the outer shell of said leg member and around the lower portion of said metallic upper extension and secured to both thereof and covering the joint therebetween and reinforcing the same.

2. An artificial leg member having an externally reduced upper end portion and depending circumferentially spaced grooves, an upper extension telescoped onto the reduced upper end portion of the leg member and having depending circumferentially spaced prongs extending into said grooves, and a socket mounted in the leg member and its extension.

3. The structure defined in claim 2 in further combination with an outer shell applied to the leg member and overlapping said upper extension and extending to a point above its prongs.

4. The structure defined in claim 2 in further combination with a band applied around the leg member and its extension at said prongs and extending above and below the same.

5. An artificial leg member having a rigid movable socket, said member having upper and lower circumferentially extended shoulders, and said socket having upper and lower circumferentially extended shoulders engaging, respectively, the upper and lower shoulders of the leg member and supporting the socket therefrom, the lower shoulder on the socket being above the lower end thereof and the lower end portion of the socket below its lower shoulder being telescoped into the leg section.

6. An artificial leg member having an upper extension applied thereto, and a socket having upper and lower circumferentially extended shoulders engaging, respectively, the upper end of said extension and the upper end of said leg member and supporting the socket therefrom, the lower shoulder on the socket being above the lower end thereof and the lower end portion of the socket below its lower shoulder being telescoped into the leg member.

In testimony whereof I affix my signature.

OTTO H. ERICKSON.
